UNITED STATES PATENT OFFICE.

CARL EMIL EGNER, OF STOCKHOLM, AND JOHAN GUNNAR HOLMSTRÖM, OF SALTSJÖ-STORÄNGEN, SWEDEN.

MULTIPLE TELEPHONE-TRANSMITTER.

1,023,557

Specification of Letters Patent.

Patented Apr. 16, 1912.

Application filed August 12, 1909. Serial No. 512,409.

To all whom it may concern:

Be it known that we, CARL EMIL EGNER, a subject of the King of Sweden, and resident of Blekingegatan 63^a, Stockholm, in the Kingdom of Sweden, and JOHAN GUNNAR HOLMSTRÖM, a subject of the King of Sweden, and resident of Saltsjö-Storängen, in the Kingdom of Sweden, have invented certain new and useful Improvements in Multiple Telephone-Transmitters, of which the following is a specification, reference being had therein to the accompanying drawing.

The effecting of great variations of the resistance in the electric circuit and the capacity of enduring strong currents are qualities necessary for a powerful telephone transmitter. In order to attain as great variations as possible in the transmitter without too great normal resistance two or more transmitters have been connected in series, as well known. The effect of such a connection of the transmitters however often is less than that of a single transmitter due to reasons easily understood. Owing to the fact that the distances between the mouth of the telephoning person and the diaphragms of the transmitters are not exactly the same and the qualities of the diaphragms and the cells of the transmitters are different, however carefully the said parts are manufactured, interference in the electric oscillations is effected, which reduces the result of the coöperation of the transmitters. Another arrangement for the same purpose consists in providing two or more transmitters behind the same diaphragm. But the result of the said arrangement has hitherto not been satisfactory, due to the impossibility of causing the transmitter cells to coöperate. The said diaphragm is divided into sonorous figures, so that different parts of the diaphragm oscillate in a different way at the same moment. Consequently the resistance of one of the cells will be reduced owing to the fact that the diaphragm swings inward at the said cell and the pressure of the same against the carbon granules of the cell is increased, while the diaphragm swings outward at another cell during the same moment, thus reducing the pressure against the carbon granules of that cell and increasing the resistance, which results in the said cells counteracting each other and the object aimed at being missed. The said lack of coöperation of the cells of multiple transmitters

hitherto used can, evidently, not be removed by adjusting the pressure between the contacts of the cells.

This invention relates to a transmitter with two or more cells so constructed that the said cells are caused to coöperate, which object is gained by combining the cells with a strained diaphragm. By straining the diaphragm it is caused to oscillate uniformly and in such manner that it oscillates with the greatest amplitude at its center part. The cells are so arranged that they receive and transform into variations of the electric resistance the very same vibrations, made by the center part of the diaphragm, so that there is a perfect synchronism in all the cells. Owing to the said synchronism it is possible to so adjust the pressure between the contacts of each cell that the sum of the actions of the cells is a maximum.

The accompanying drawing shows in a cross section part of a multiple transmitter arranged in accordance with this invention.

The diaphragm 1 is jammed between the casing 2 of the transmitter and a ring 3, fixed to the casing in any suitable manner. 4 is a ring-shaped inner edge of the casing 2, against which the diaphragm 1 is bearing. The straining of the diaphragm is effected by a ring 5 forcing the diaphragm into the groove 6 between the edge 4 and the wall of the casing 2. The said ring 5 is forced inward by means of thumb-nuts 7 or in any other suitable manner and strains the diaphragm uniformly from its center outward. Instead of fixing each of the movable electrodes of the cells separately to the diaphragm 1, a disk 8 is fixed to the diaphragm by means of a screw pin 9 at the center of the same. At the periphery of the said disk 8 a plurality of electrode disks or pieces 10 are fixed, one of which is shown in the drawing. A hollow perforated cylinder 11, of steel or any other hard material is mounted between the disk 8 and the diaphragm 1. Consequently, the said disk 8 with the electrode disks 10 will vibrate just in the same manner as the center part of the diaphragm 1 and full synchronism at all the disks 10 will be attained, so that the said disks 10 move downward simultaneously and upward simultaneously, thus effecting the same variations in all the cells during the same periods. The electrode disks 10 are insulated from the disk 8 and mutually and are connected

by conductors 12 with the insulated clamping nuts 13 on the outer side of the diaphragm 1. Each of the electrodes 10 extends downward into a subjacent cup 14. 5 The said cups, which form the other electrode of the respective cells, are insulated mutually and from the other parts of the apparatus, the cups being for that reason supported by plungers 15, fitting in cylinders 16, which are mounted in a plate 17 of an insulating material and common to all the said cylinders 16. Each of the cups 14 can be adjusted with relation to the electrode 10 *i. e.* the pressure between the electrode 10 and the carbon granules 18 in the cup can be adjusted to the most suitable one. As a screw 19 bearing against the lower end of the plunger 15 is moved inward the plunger 15 and the cup 14 are raised, and as the screw is moved outward the plunger 15 and the cup 14 will follow the same owing to the pressure of a spring 20 fixed to a stationary part of the apparatus and acting downward upon the plunger 15. The said spring 20 also serves as a conductor between the cup 14 and the respective outer contact or clamping nut 21.

When the described transmitter is to be adjusted the cells are separately and in turn connected with the circuit and adjusted by means of the corresponding screw 19, so that the greatest effect is gained. In order that absolutely the same adjustment may be made in all the cells the said adjusting operation must be effected in such manner, that after each of the cells has once been adjusted the adjusting operation is again started with the first cell and is then continued cell by cell, the said operation being thus repeated two or three times. In the said manner the cells are caused to coöperate exactly and a specially great effect is gained.

When each of the cells has been adjusted in the described manner by means of the screw 19, so that there is the same pressure in all the cells, it may be necessary during the operation of the transmitter to somewhat increase or decrease the said pressure. The adjusting of each cell separately for the said purpose would, evidently, be very time-consuming and unpractical, as each cell then must be adjusted at least twice. For that reason the transmitter in question is provided with a device, by means of which all the cells can be uniformly and simultaneously adjusted, after the same pressure has been effected in all the cells. For the said purpose the insulating plate 17, supporting all the plungers 15 of the cups or

cells 14 can be moved upward and downward (without being rotated) by rotating a ring 22. The said ring 22, which can be rotated horizontally, is prevented from moving vertically by screw-pins 23, engaging a groove provided in a stationary boss 24 inclosing the plate 17. A screw-threaded ring 25 fixed to the plate 17 and engaged by the ring 22 is caused by the rotated ring 22 to move vertically parallelly to itself, thus raising or lowering the plate 17 and all the cups 14. The plate 17 is prevented from rotating by the springs 20 and by one or more vertical ribs 26 engaging grooves 27 provided in the said boss 24, for instance.

Having now described our invention, what we claim as new and desire to secure by Letters Patent is:

1. In multiple telephone transmitters, the combination of a diaphragm uniformly strained from its center toward its periphery, a disk firmly secured to an extended surface of the central portion of the diaphragm, substantially as great as the said disk, and a plurality of rigid members fixed to the said disk and forming one of the electrodes of respective transmitter cells.

2. In multiple telephone transmitters, the combination of a diaphragm uniformly strained from its center toward its periphery, a disk fixed to the center part of the diaphragm, an interposed piece of hard material between the diaphragm and the said disk, and of substantially the same diameter as the disk, the said interposed piece bearing with its ends against the diaphragm and the disk respectively, and a plurality of rigid members fixed to the aforesaid disk and forming one of the electrodes of respective transmitter cells.

3. In telephone transmitters, the combination of a diaphragm uniformly strained outward from its center, a plurality of members forming one of the electrodes of respective transmitter cells, a disk fixed to the center part of the diaphragm and supporting the said electrode-members, and a hollow interposed piece of hard material between the diaphragm and the said disk, and arranged like a grating, substantially as described and for the purpose set forth.

In witness whereof, we have hereunto signed our names in presence of two subscribing witnesses.

CARL EMIL EGNÉR.

JOHAN GUNNAR HOLMSTRÖM.
